(57) CLAIM

The ornamental design for a back brush long handle, as shown and described.

DESCRIPTION

FIG. 1 is the front and left, top perspective of the back brush long handle showing my new design;

FIG. 2 is the back and and right, back perspective of the back brush long handle showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1; and, FIG. 10 is an exploded rear perspective view thereof.

The dash-dash broken lines immediately adjacent to the shaded areas depict the bounds of the claimed design, while all other broken lines are directed to environment. The dash-dash broken lines form no part of the claimed design. The dot-dash broken lines indicate an enlargement portion of the design and form no part of the claimed design.

1 Claim, 10 Drawing Sheets
